US0D1088684S

(12) **United States Design Patent** (10) Patent No.: **US D1,088,684 S**
(45) Date of Patent: ** Aug. 19, 2025

(54) **ESPRESSO MACHINE**

(71) Applicant: **WHIRLPOOL CORPORATION**,
Benton Harbor, MI (US)

(72) Inventors: **Kaito Choy**, St. Joseph, MI (US); **John W. McConnell**, St. Joseph, MI (US);
Ben C. Shao, Clarendon Hills, IL (US);
Zhaoyi Yin, St. Joseph, MI (US)

(73) Assignee: **WHIRLPOOL CORPORATION**,
Benton Harbor, MI (US)

(**) Term: **15 Years**

(21) Appl. No.: **29/977,333**

(22) Filed: **Dec. 6, 2024**

(57) **CLAIM**

The ornamental design for an espresso machine as shown and described.

DESCRIPTION

FIG. 1 is a perspective view of an espresso machine according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in broken line form no part of the claimed design.

1 Claim, 7 Drawing Sheets
